UNITED STATES PATENT OFFICE.

FRANK GARRISON, OF JEROME, IDAHO.

TOOL.

Application filed April 5, 1922. Serial No. 549,925.

To all whom it may concern:

Be it known that I, FRANK GARRISON, a citizen of the United States, and a resident of Jerome, in the county of Lincoln and 5 State of Idaho, have invented certain new and useful Improvements in Tools, of which the following is a specification.

This invention relates in general to tools such as pliers, pinchers or the like, and the 10 object of the invention is to provide a tool of this character which embodies foldable handle members whereby the tool when not in use may be folded up into a compact article capable of being carried around in 15 the pocket without discomfort and inconvenience and which at the same time when not folded but arranged in operative position is susceptible of effective use, the organization being such that the capacity of 20 the tool to carry out its normal functions are in nowise impaired by its foldable qualities.

Other objects and advantages of the invention reside in certain novel features of 25 the construction, combination and arrangement of parts which will be hereinafter more fully described and particularly pointed out in the appended claims, reference being had to the accompanying drawings 30 forming part of this specification, and in which:

Figure 1 is a perspective view, showing the preferred embodiment of the invention;

Figure 2 is a plan view, showing the parts 35 in folded position;

Figure 3 is an end view of Figure 2; and

Figure 4 is a view partly in side elevation and partly in section, and showing in dotted and in dot and dash lines the parts in various 40 positions.

Referring to the drawings wherein for the sake of illustration is shown the preferred embodiment of the invention, the numeral 10 designates the jaws of the pliers or pinchers or the like, which are integrally formed with the handle members, designated at 11, the handle members being crossed and pivotally connected, as indicated at 12. The handle members 11 are of 45 identical construction although oppositely arranged and each handle member 11 includes a pair of sections, designated at 13 and 14, the section 13 being integral with its jaw 10 and the section 14 being pivotally 50 connected to the section 13 by means of a

hinge joint 15. The hinge joint 15 permits the folding of the section 14 back on the section 13 and each section 13 is provided with a concaved face 16 against which a correspondingly formed convexed face 14⁶⁰ of its section 14 is snugly fitted in the folded position. In the extended or operative positions of the sections of the handle the parts are positioned as shown in full lines in Figure 4 and in such position the coacting shoulders of the hinge joint 15 which are formed on the sections 13 and 14 respectively and which are designated at 17 and 18 respectively are engaged to take up the strain and thus endow the tool with a 70 capacity to grip the work or object to be operated on with the desired force. Each section 14 carries a blade spring 19 which is received in the cavity 20 provided therefor on the inner face of the section 14. One 75 end of the blade spring is secured, as at 21, to its section 14 and the other end extends over the hinge joint 15 and is provided with an inturned shoulder or lug 22. The sections 13 of the handle members are provided 80 with sockets 23 adjacent the hinge joints and on the inner side of the sections and these sockets are adapted to receive the lugs or shoulders 22 in the operative position of the handles so as to prevent accidental folding of the sections of the handle. Opposite the sockets 17 the ears of the hinge joint 15 are also provided with similar sockets or depressions 24 into which the shoulders or lugs 22 are spring pressed in the folded position of the handles to prevent accidental 85 displacement. Adjacent the lug 22 thereof the spring 19 projects or is disposed above the adjacent parts so that it may be readily grasped by the fingers and flexed to disengage the lug 22 from either the sockets 23 or 24 and thus permit of folding or of unfolding of the handle members. 90

The tool thus constituted possesses all of the capacities and advantages of a tool having one piece and integral handle and at the same time it can be folded to provide a compact tool which may be conveniently carried around in the pocket or may be conveniently stored in a compact space. 105

I claim:

1. A tool having jaws and pivotally connected handle members carrying said jaws, each handle being made up of a pair of pivotally connected sections, one of the sections 110

having a concaved face against which the other section is adapted to be snugly fitted in the folded position.

2. A tool having jaws and pivotally connected handle members carrying said jaws, each handle being made up of a pair of pivotally connected sections, one of the sections having a concaved face against which the other section is adapted to be snugly fitted in the folded position, and releasable means for holding the sections in folded or unfolded position.

3. In a tool of the character described, a pair of pivotally connected handle members, each pair being made up of a pair of pivotally connected sections, and a spring carried by one of the sections and cooperating with the other section for releasably holding the sections in folded or unfolded position.

4. In a tool of the character described, a pair of handle members, each handle member being made up of a pair of sections, a hinge joint connecting the sections of each handle member, each of said hinge joints having coacting shoulders engageable in the extended positions of the sections, a blade spring fixed to one of the sections and extending over the hinge joint, the portion of the spring extending over the hinge joint being provided with an angularly extended lug, said hinge joint and the other section being provided with sockets into which the lug is adapted to be removably received.

FRANK GARRISON.
